UNITED STATES PATENT OFFICE.

PATRICK HENNESSY, OF DERBY, CONNECTICUT.

DESIGN FOR A NECKTIE-HOLDER.

SPECIFICATION forming part of Design No. 25,771, dated July 14, 1896.

Application filed May 27, 1896. Serial No. 593,352. Term of patent 7 years.

To all whom it may concern:

Be it known that I, PATRICK HENNESSY, of Derby, in the county of New Haven and State of Connecticut, have invented a new 5 Design for Necktie-Holders; and I do hereby declare the following, when taken in connection with the accompanying drawing, and the letters of reference marked thereon, to be a full, clear, and exact description of the same, 10 and which said drawing constitutes part of this specification and represents a perspective view of a necktie-holder embodying my design.

This invention relates to a design for necktie-holders; and it consists in the form of the 15 holder as hereinafter described, and shown in the accompanying illustration.

In general outline the holder is oval and comprises a plate A, which has near its upper end a perforation B, which opens at its lower 20 end into a slot C. Projecting from the upper end of the plate A is a narrow tongue D, which extends outward and downward in a plane substantially parallel to the plate A, all as shown in the accompanying illustration. 25

I claim—

The design for necktie-holders as herein shown and described.

In testimony whereof I have signed this specification in the presence of two subscribing witnesses. 30

PATRICK HENNESSY.
